Int. Cl. D9—03
Term of patent 14 years

U.S. Cl. D9—219

FIG. 3

FIG. 2

FIG. 1

FIG. 1 is a perspective view of a molded packaging tray for meat or the like showing our new design;

FIG. 2 is a front elevation view; and

FIG. 3 is a bottom plan view.

The characteristic feature of the design resides in the inverted V-shaped ribs forming the open-window bottom in combination with the bulged or fluted indentations in the side walls into which the inverted V-shaped ribs merge, and the configuration of the open windows, as shown.

We claim:

The ornamental design for a molded packaging tray for meat or the like, as shown and described.
